Attorney.

UNITED STATES PATENT OFFICE.

EMIL F. HAFELFINGER, OF WEEHAWKEN, NEW JERSEY.

STRING-TENSIONER FOR VIOLINS.

1,361,049.

Specification of Letters Patent. Patented Dec. 7, 1920.

Application filed July 24, 1919. Serial No. 312,934.

To all whom it may concern:

Be it known that I, EMIL F. HAFELFINGER, a citizen of the United States, residing in Weehawken, in the county of Hudson, 5 son and State of New Jersey, have invented certain new and useful Improvements in String-Tensioners for Violins, of which the following is a specification.

This invention relates to means for tensioning the strings of violins and other musical instruments.

The object of my invention is to simplify and improve the mounting of the string-adjusting elbow-lever or bell-crank mounted 15 in the end of the bracket usually attached to the tail-piece of a violin, and to make it less expensive to manufacture, while producing a joint or articulation which is practicable, and not liable to permit the bell-20 crank to become loose or otherwise to cause trouble.

To effect these objects I form an opening, preferably two oblong slots extending lengthwise of the bracket. The outer slot, 25 which is permanently closed at its outer end, is intended to receive the upright arm of the elbow-lever, which arm is provided with cutaways upon its opposite sides. By this operation opposing integral shoulders 30 are left on each of the opposite sides of the elbow-lever, to engage the edges of the bracket slot, and thus afford a bearing or fulcrum for the elbow-lever.

The inner of the two slots is used principally for the purpose of providing a way 35 for the bell-crank to be introduced into the outer slot, where said bell-crank is provided with a head, to which the string is attached, and this inner or second slot is made of 40 relatively large size, with a view to affording room for said head to pass therethrough.

The inner or second slot is expanded 45 enough to permit passage therethrough of the head. The metal or partition between the slots is split wide enough to permit the cutaway portion of the elbow-lever to be slipped or passed bodily therethrough into the narrow outer slot.

The next operation is to press the bulged-50 out integral sides of the bracket back again to substantially their original positions, thereby restoring the shape of the inner opening to its original long slotted shape, and also closing the split between the two 55 slots or openings, and shaping the outer slot to the parallel sides of the elbow lever at

its cutaway portion. The device is capable of withstanding successfully the stresses to which the bearing is subjected in the tensioning of the music wire.

Another feature of the improvement resides in the construction of the head upon the tensioning lever. It has been the practice to provide a peripheral groove in said head to receive a loop which is usually 65 formed upon the end of the music wire. One of the objects of the invention is to adapt the device also for wires or strings which are not provided with said loops, and to this end the peripheral groove in the 70 head is enlarged in width, and a diametrical hole is drilled through the head within said groove, so that an end of the music wire or string may be threaded through said hole, a knot being formed upon the end of 75 the string to prevent it from slipping out of the hole. Thus the lever is adapted for different kinds of strings, and its utility substantially increased.

Other features and advantages will here- 80 inafter appear.

In the accompanying drawings,

Figure 1 is a diagrammatic side elevation of a violin, showing the present improvements applied thereto.

Fig. 2 is a perspective view of the string-adjusting device ready for attachment to a violin or other musical instrument.

Fig. 3 is a perspective view of the im- 90 proved elbow-lever or bell-crank.

Fig. 4 is a sectional end elevation and Fig. 5 a sectional side elevation of the assembled lever and bracket seen at Fig. 2. This figure shows a knot made in the string which is passed through a hole in the lever, 95 the knot preventing the string from being pulled out of the hole.

Fig. 6 is a sectional view of the head of the lever, with the looped end of a string caught in the groove.

Fig. 7 is a plan of a bracket with its perforations, but before it is operated upon to prepare it for the articulation of the lever thereto.

Fig. 8 is a perspective of one form of 105 taper punch or tool by which is opened the inner long closed slot seen at Fig. 7, whereby said slot is made of nearly circular form, and the portion of the bracket between the inner and outer slots is split, forming a 110 communication between the slots.

Fig. 9 shows the bracket after its slots

have been opened and the split made between the slots, and illustrates the manner of inserting the string arm of the elbow-lever, the head thereof being introduced in 5 the enlarged rounded hole in the bracket.

Fig. 9 shows a spring.

Fig. 10 shows the next step in articulation, the thinned portion of the lever being slipped through the opening between the 10 large slot and the small slot, and occupying a permanent position in the small slot.

Fig. 11 shows how the large and small slots are restored or closed by a die, so as to lock the shank of the elbow-lever in the 15 small slot; the bracket now having substantially the original appearance seen at Fig. 7, and showing a whole or unbroken integral end at the point where the lever is articulated thereto.

20 A violin or other musical instrument 20 may have a bridge 21 over which passes a wire or other string 22, as, for example, an "E" string, which at one end may be caught upon the usual peg or otherwise, and at the 25 other end is caught upon an upright arm 24 of a tensioning lever, said arm having a head 25 provided with a peripheral groove 26 to receive a loop 27 formed upon the wire 22, Fig. 6. The lever arm 24 is mounted to 30 be adjustable to the left and right in Fig. 1, and, for this purpose, is pivotally mounted upon a bracket 28, which has at its right-hand or rear end a stud 29 to pass up through a hole in the tail-piece 30 usually 35 provided upon the violin for retaining the strings. A nut 31 is threaded upon said stud, to screw down upon the tail-piece and hold the bracket thereto. Said stud 29 is hollow, and a thumb-screw 32 is threaded 40 therethrough so that its tip will bear down upon the tip of an adjusting arm 33 which is made integral with the arm 24, so as to swing the latter about its pivot and thereby effect fine adjustments in the tensioning 45 of the string 22; the arms 24 and 33 taken together forming an elbow-lever.

The bracket 28 may be made of "quarter hard" or other soft sheet-steel, or preferably a length of flattened soft steel wire; and a 50 hole 34 is made at one end thereof to receive the stud 29. At the other end of the bracket are formed two openings, perforations or slots end to end, the outer slot 35 of a size to fit a thinned portion 36 of the 55 arm at the base thereof, this portion being thinned by making parallel cuts or stamping or otherwise forming flats 37 in its opposite sides, to give it a nearly rectangular shape, as seen at Fig. 10. The inner slot 38 is 60 formed in said bracket near said outer slot, and may be larger than the latter.

The next step is to force any suitable pointed shank or tool 39, Fig. 8, into the inner slot 38, to expand the same into the 65 shape of a roughly circular hole 38^a, as at

Fig. 9. This operation also splits at 40 the portion of the metal of the bracket which is seen between the two slots at Fig. 7.

The head 25 of arm 24 is then introduced into the enlarged hole 38^a in the bracket, 70 as at Fig. 9, and the thinned part of the arm or post 24 is passed through the split 40 between the slots, into the outer slot 35^a, as at Fig. 10.

Then the bracket is placed between the 75 jaws 41 of a die, Fig. 10, and the jaws are brought together, as at Fig. 11, to close both openings 35^a and 38^a, returning them substantially to their original Fig. 7 condition, as at Fig. 11; the split 40 between the slots 80 closing up, and the elbow-lever or bell-crank 24, 33 being securely and permanently locked in the outer slot 35, Fig. 11, by the forced-in walls of the bracket, the walls being confined between the shoulders 85 on the opposite sides of the lever. The articulation of the lever to the bracket is thus completed, since the edges of the hole 35 upon the opposite sides of the thinned portion 36 form walls or bearings upon which 90 rest the convex integral shoulders 42 formed by the cutaways or stampings in the lever, whereby the bell-crank is in effect pivoted to the bracket, but without the slow and costly drilling, fitting and other operations 95 heretofore necessary. It will be observed that the device may be manufactured by using the same tools for some operations as were used for previous tensioning devices, and that a largely increased output 100 will result from the same amount of labor.

It will be seen that the end 43 of the bracket is never opened or broken, but remains permanently whole or unseparated, and that consequently there is no liability 105 of the bell-crank slipping out. In other words, the end of the bracket is unbroken, where the strain comes when the string is tensioned. There is no possibility of the end of the bracket tending to divide, and any 110 stress which occurs at the articulation of the lever to the bracket tends if anything to lengthen the bracket and close the sides of the slots.

The tip of the bell-crank arm 33 is 115 widened, as seen at Fig. 3, at the point where it is engageable by the adjusting screw, and this width permits a certain lateral play of the bell-crank without liability of escape from the control of the screw. The widening which is illustrated at said figure will prove ample when the bracket is mounted according to the present invention, since the sides of the slot 35 may fit quite snugly to the thinned sides of the lever arm, and prevent undue lateral vibration thereof. Moreover, the slot makes a permanent fitting to said flattened lever sides, avoiding the liability heretofore experienced of looseness occurring at the pivotal joint, such looseness 120

125 130

being multiplied at the tip of the operating arm 33.

At Fig. 5 is shown a wire or string for a musical instrument provided with a knotted end 44, said string being passed through a perforation 45 in the head 25 of the lever arm, and the knot serving in place of a loop for retaining the string. This hole is made in the head within the groove, so that 10 the device will answer for either loop or knot.

At Fig. 9^a is shown a thin spring finger 46 having a hole 47 to fit on stud 29, Fig. 5, and to be clamped between bracket 28 and tail-piece 30 by nut 31. The spring terminates in a rising finger 49 having at its tip a crotch 50 to catch upon the arm 24, to prevent the lever arm 33 from flying down and damaging the violin when string 22 20 snaps.

The punching tool 39, Fig. 8, may have a nib or key 39^a, to enter the passageway at 40 in the blank, and smooth its sides, or eliminate any roughness that may occur at 25 the splitting of the partition between the openings.

Variations may be resorted to within the scope of the invention, and portions of the improvements may be used without others.

Having thus described my invention, I claim:

1. The combination of a bracket provided with means for attachment to a musical instrument, and a lever having one arm for attachment to a string and another arm whereby the lever may be adjusted, said adjusting arm extending along the bracket and the latter having adjusting means to engage the lever to tension the string; said lever having recesses on its opposite sides to form shoulders, and said bracket having two holes in one of which the lever is articulated at said recesses, a closed split extending from one of said holes to the other.

45 2. As a new article of manufacture, means for adjusting the string of a musical instrument comprising a bracket having means for attaching it to the instrument and a lever articulated to said bracket, the lever having recessed portions on its opposite sides to form shoulders, and the bracket having an outer opening in which the recessed portions of said lever loosely fit, the shoulders of the lever fulcruming upon the edges of the opening, the bracket at the outer end of said opening being whole or unbroken and said bracket having an inner introductory opening, and a permanently closed passage from the inner to the outer opening.

60 3. The combination of a bracket having means for attachment to a musical instrument, and having a whole or unbroken end, an opening being formed in the bracket near said whole end, and a string-tensioning lever 65 having a shouldered fulcrum portion, the

portion of the lever next to said shouldered portion fitting in said opening in said bracket.

4. The combination of a bracket having means for attachment to a musical instrument, and having a whole or unbroken end, an opening being formed in the bracket near said whole end, and a string tensioning lever having a shouldered fulcrum portion, the portion of the lever next to said shouldered portion fitting in said opening in said bracket, said lever having an enlarged head, and said bracket also having a large opening and a closed passage between said openings.

5. As a new article of manufacture, means 80 for adjusting the string of a musical instrument, comprising a bracket having means for attaching it to the instrument and a lever articulated to said bracket, the lever having recessed portions on its opposite sides 85 to form shoulders, and the bracket having a closed opening in which the recessed portions of said lever loosely fit, the shoulders of the lever fulcruming upon the edges of the opening, the bracket at the outer end of 90 said opening being whole or unbroken, and said bracket having an inner opening, the metal between said openings having a closed split.

6. As a new article of manufacture, a two-part device for string adjustment, one part being a lever to which the string is attached, the other part being a bracket having means for attaching it to an instrument, said parts articulated by means of a cutaway portion 100 in the lever fitted in a closed oblong perforation in the bracket, said bracket having in its body an adjacent communicating introductory perforation sufficiently closed to confine the lever within the first perforation. 105

7. The combination of a bracket to be fastened to the tail-piece of a violin, and a string-tensioning lever formed in one piece and having opposite integral shoulders, said bracket having a whole or unbroken integral end and said lever directly articulated to said bracket at said end, said bracket having a perforation at the point of articulation and also having a forced-in wall at said perforation, said lever being both confined 110 within said perforation and fulcrumed upon said bracket by means of said shoulders, and said wall being confined between said shoulders and permanently locking the lever to the bracket.

8. The combination of a bracket to be fastened to the tail-piece of a violin, and a string-tensioning lever formed in one piece and having opposing integral shoulders upon each of its opposite sides, said bracket 125 having a whole or unbroken integral end and said lever directly articulated to said bracket at said end; said bracket having a perforation at the point of articulation and also having opposite forced-in walls at said 130

4
perforation, said lever extending between said walls and being fulcrumed upon said bracket by means of said shoulders, and said walls being confined between the shoulders 5 upon the opposite sides of the lever and permanently locking the lever to the bracket.

9. The combination of a bracket having means for attachment to a musical instrument, and having a whole or unbroken end, 10 an opening being formed in the bracket near said whole end, said bracket having a

forced-in portion at said opening, and a string-tensioning lever having integral shouldered fulcrum portions above and below said bracket, the portion of the lever between said shouldered portions fitting in said opening in said bracket and permanently interlocked therewith by said forced-in portion of the bracket. 15
